DESIGN FOR A DISPLAY RACK

Horace A. Sarvis, Lansing, Mich.

Application September 25, 1940, Serial No. 95,352

Term of patent 14 years

To all whom it may concern:

Be it known that I, Horace A. Sarvis, a citizen of the United State and a resident of Lansing, in the county of Ingham and State of Michigan, have invented a new, original, and ornamental Design for a Display Rack, of which the following is a specification, reference being had to the accompanying drawing, forming a part thereof.

In the drawing:

Figure 1 is a front perspective view of a display rack embodying my new design; and

Figure 2 is a top plan view of the display rack shown in Figure 1.

The shading of the display rack shown in Figures 1 and 2 is to indicate a lustrous metal finish.

I claim:

The ornamental design for a display rack, substantially as shown and described.

HORACE A. SARVIS.
